UNITED STATES PATENT OFFICE

95,929

DESIGN FOR A PALL-BEARER'S BADGE

Carl D. Roberts, Kirbyville, Tex.

Application April 2, 1935, Serial No. 56,185

Term of patent 7 years

To all whom it may concern:

Be it known that I, Carl D. Roberts, a citizen of the United States, residing at Kirbyville, in the county of Jasper and State of Texas, have invented a new, original, and ornamental Design for Pall-Bearer's Badge, of which the following is a specification, reference being had to the accompanying drawing, forming part thereof.

I claim:

The ornamental design for a pall-bearer's badge, as shown.

CARL D. ROBERTS.
